LOCKING DEVICE FOR A CASEMENT TYPE WINDOW

Robert H. Bliss, Jr., East Syracuse, N.Y.

Application October 24, 1951, Serial No. 252,867

2 Claims. (Cl. 292—101)

1

This invention relates to locking devices for casement type windows, and to a method for permanently assembling such locking devices on casement windows, particularly basement or utility type casement windows. More particularly, the invention relates to locking devices of the kind which comprise a locking handle pivoted to the ventilators of windows of the types mentioned above in such a way that in each instance, when the ventilator is moved into its closed position with respect to the frame of the window, one end of the locking handle is positioned to cooperate with a fixed surface on the frame of the window so that the ventilator may then be drawn into close engagement with the frame by movement of the free end of the locking handle. Generally, there is provided on the ventilator a hook device which acts to maintain the locking handle in its closed position.

One of the principal purposes of this invention is to provide a locking device for a casement type window of the kind referred to above in which the locking handle is fixed to the ventilator in a manner which eliminates the need for fastening devices or for devices to provide a pivotal support for the locking handle. A further purpose of the invention is to provide a locking device which permits the use of snap-in screens in conjunction with the casement window without interfering with the normal operation of the locking device.

Another purpose of the invention is to provide a method of fabricating a casement window employing a locking handle so that the locking handle may be properly supported on, and permanently connected to, the ventilator of the casement window without the necessity of employing fastening devices or devices to provide a pivotal support for the locking handle.

Other objects and advantages of the invention will be apparent from the following description thereof which is made with reference to the accompanying drawings. It will be understood that the detailed description made with reference to the drawings is for the purpose of facilitating an understanding of the invention, and is not to be construed as limiting the invention to the particular details revealed, except as such matters may be specified in the appended claims.

In the accompanying drawings:

Figure 1 is a rear elevational view of a casement type of window employing a locking device of the kind provided by this invention;

Figure 2 is a vertical sectional view on line 2—2 of Figure 1;

2

Figure 3 is a view on line 3—3 of Figure 2 showing in detail the relationship between the upper end of the locking handle and the upper horizontal ventilator bar;

5 Figure 4 is a view on line 4—4 of Figure 2 showing in detail the manner in which the handle hook cooperates with the lower end of the locking handle to secure the handle in its window locking position;

10 Figure 5 is a perspective view of the upper end of the locking handle showing particularly the arcuate section which passes through a pivot slot provided in the upper horizontal ventilator bar, as well as the locking tip of the handle which engages a fixed surface on the upper horizontal frame bar;

15 Figure 6 is a partial vertical section through the casement window frame and the ventilator showing the ventilator in an open position;

20 Figure 7 is a similar vertical sectional view showing the ventilator in its closed position with respect to the frame, and also showing the locking handle in a position through which it passes as it is moved toward its locking position;

25 Figure 8 is a partial vertical sectional view showing the upper horizontal ventilator frame bar, and in dotted lines, the position to which the inner flange of this ventilator frame bar is bent preliminarily to inserting the locking handle into a slot provided in the bar;

30 Figure 9 is a similar view showing the lower end of the locking bar partially passed through the slot provided in the inner flange of the upper horizontal ventilator bar; and

35 Figure 10 is a similar vertical sectional view showing the locking handle in operative position within the slot in the upper horizontal ventilator bar, the dotted lines illustrating the position to which the upper flange is returned after the locking handle has been inserted.

40 A casement window of the kind to which this invention is applicable is illustrated in Figure 1. The window therein illustrated comprises a frame member 20 and a companion ventilator member 22, both the frame and the ventilator member being made up of rectilinear Z-bars which are joined together to provide rigid rectangular units. The length and width of the ventilator member is sufficiently less than the corresponding dimension of the frame member so that the ventilator may be received within the frame member with the outer edges of the ventilator engaging the inner edges of the frame member.

45 The cross-sectional form of the Z-bars of the frame and ventilator members, seen most clearly

in Figures 2 and 7, is such that a double sealing contact is obtained between the ventilator member and the frame member when the window is in its closed position. In the window illustrated, the mutually facing flanges of the lower horizontal Z-bar 25 of the ventilator and the lower horizontal Z-bar 27 of the frame are arranged to provide a pivotal connection between the ventilator and the frame member. This aspect of the window construction illustrated forms no part of the present invention.

A locking device for the window comprises the locking handle 24 having a lengthy shank portion 26 and a locking tip 28. Intermediate the shank 26 and the tip 28 is an arcuate section 30 which is designed to be received in an aperture 32 provided in the upper horizontal Z-bar 29 of the ventilator member 22. As seen best in Figure 3, intermediate the arcuate section 30 and the locking tip 28 the locking handle is enlarged at 31 to a width which is greater than the width of the slot 32, thereby preventing the locking handle from being withdrawn from the slot by an inwardly directed pull on the handle shank.

Referring to Figure 2, it will be seen that the arcuate curvature of the section 30 is such that the upward pivotal movement of the locking handle is limited by the engagement of the underside of the enlarged portion 31 of the handle with the top surface of the web 36 of the upper horizontal ventilator Z-bar 29. This upper limited position of the handle is illustrated in dotted lines in Figure 2. It will be observed that in this limited position the end of the locking tip 28 is sufficiently close to the surface of the web 36 to permit the ventilator to be swung to the open position illustrated in Figure 6 without the locking tip striking against the inwardly extending flange 38 on the upper horizontal Z-bar 29 of the frame member. The arrangement of the locking handle as described above prevents the locking handle from being pivoted upwardly to the extent that the arcuate section 30 can be caused to pass through the slot 32 and the handle thereby withdrawn from association with the ventilator member. It will be seen, therefore, that withdrawal of the handle from the ventilator is prevented in the one direction by the enlarged portion 31 intermediate the locking tip 28 and the arcuate section 30, and in the other direction by the arrangement of the arcuate section 30 and the enlarged portion 31 with respect to the web 36 which limits the handle from being pivoted upwardly to the extent that the arcuate section 30 can be caused to pass through the slot 32.

A fixed surface is provided on the frame member 20 with which the locking tip cooperates to lock the window in its closed condition. In the embodiment illustrated in the drawings, this cooperating locking surface is the outwardly facing wall of an aperture 40 provided in the upper horizontal Z-bar 38 of the frame member 20. As the ventilator is moved from an open position, such as that indicated in Figure 6, the locking handle is adapted to be pivoted upwardly to its limit of pivotal movement and there held until the locking tip 28 passes beneath the inwardly extending flange 38 of the upper horizontal Z-bar 29 of the frame member. As the window closely approaches its closed position, which is illustrated in Figure 2, the locking handle is pivoted downwardly from the dotted line position shown in Figure 2 to the solid line position, in the course of which the locking tip 28 engages the outwardly

facing wall of the aperture 40. This engagement will normally occur before the ventilator has reached its fully closed position. Thereafter, the locking handle is moved downwardly and, with the wall of the aperture 40 acting as a fulcrum point for the locking handle, the locking handle forces the ventilator into its fully closed position with respect to the frame member. Thereafter, the distal end of the locking handle is positioned within, and retained by, the handle hook 44 which is fixed to the lower horizontal Z-bar 25 of the ventilator. The slot 32 slightly exceeds in depth the depth of the arcuate portion 30 of the handle, so that the distal end of the handle may be moved laterally sufficiently to permit the end of handle to be engaged and disengaged from the hook 44. The window thus remains securely locked until the lower end of the locking handle is released from the hook 44 and the handle is pivoted upwardly to withdraw the locking tip from engagement with the outwardly facing wall of the aperture 40.

A major advantage of the construction of the locking device described above is that snap-on type of screen may be employed with the casement window without interfering with the normal operation of the locking device. It may be seen from Figure 6 that a screen member 46 may be interposed between the inwardly extending flanges 48, 50 of the frame member and the ventilator, respectively, and, although the interposed screen will prevent a flush engagement of these flanges, as is normally the case when the window is closed, the arcuate section of the locking handle and the elongated shank portion are sufficiently resilient to permit the distal end of the handle to be placed behind the locking handle hook 44 even when the screen is employed.

A method of fabricating a casement window employing a locking device of the kind described above which avoids the necessity of employing fastening devices or other devices normally used to provide a pivotal support for a locking handle is illustrated in Figures 8-10.

A cross-section of the upper horizontal Z-bar 29 of the ventilator member 22 is shown in Figure 8 in solid lines. According to the instant method, the portion of the upwardly extending lateral flange 33 of this Z-bar in which the slot 32 is provided is bent to the dotted line position illustrated in Figure 8. As previously mentioned, the portion of the handle intermediate the locking tip 28 and the arcuate section 30 is enlarged as at 31 to the extent that it cannot be passed by the slot 32. While the upwardly extending flange 33 is bent as described, the distal end of the locking handle 24 is passed through the slot 32 and drawn through the slot until the arcuate section 30 of the handle passes freely into the slot without interference from the upwardly extending flange 54 or the upper surface of the web 36 of the Z-bar 29. Thereafter, the bent portion of the upwardly extending flange is returned from the solid line position illustrated in Figure 10 to the dotted line position therein, wherein the lateral flanges of the Z-bar 29 are again parallel throughout to one another and positioned to make a flush engagement with the corresponding parallel flanges of the upper horizontal Z-bar of the frame member.

It will be clear from the foregoing description of the instant window locking device that its use is not limited to casement windows in which the

ventilator is arranged to pivot with respect to the frame member about a horizontal axis or in any other particular manner, and that it is particularly adapted for use on basement windows which are positioned so that they can not otherwise be conveniently reached to open and close them.

Having thus described my invention what I claim as my invention and desire to secure by Letters Patent is:

1. A locking device for a casement type window of the kind having a frame member and a cooperating ventilator member engageable by said frame member when the window is closed, said locking device comprising a locking handle having an arcuate bend towards one end thereof, a locking tip extending from one side of said bend and the shank of said handle extending from the other side thereof, a slot provided in said ventilator member, the arcuately bent portion of said handle being received loosely in said slot, said handle being enlarged between said locking tip and said arcuately bent portion to prevent said handle from being withdrawn from said slot in one direction, a surface on said ventilator provided beneath said enlarged portion of said handle to prevent said handle from being pivoted sufficiently to be withdrawn from said slot in the other direction, and said locking tip being adapted to engage a surface on a frame member.

5 2. A locking device for a casement window of the kind having rigid rectangular frame and ventilator members comprising Z-bars, the corresponding lateral flanges of said frame and ventilator Z-bars engaging one another respectively, when said window is closed, said locking device comprising an elongated locking handle having towards one end an arcuate section positioned within an aperture provided in the lateral flange of one of the Z-bars of said ventilator, the one end of said handle comprising a locking tip adapted to engage a surface on a frame member, said handle being enlarged in cross-section intermediate said tip and arcuate section to a width greater than that of said slot to prevent said handle from being withdrawn from said aperture in one direction, and the enlarged portion of said handle being positioned above the web of the said one Z-bar to prevent said handle from being pivoted sufficiently to be withdrawn from said aperture in the other direction.
